DRINK MIXER

W. Arthur Ernst, Racine, Wis.

Application July 25, 1949, Serial No. 4,123

Term of patent 14 years

(Cl. D44—1)

To all whom it may concern:

Be it known that I, W. Arthur Ernst, a citizen of the United States, residing at Racine, in the county of Racine and State of Wisconsin, have invented a new, original, and ornamental Design for a Drink Mixer, of which the following is a specification, reference being had to the accompanying drawing, forming part thereof.

I claim:

The ornamental design for a drink mixer, as shown.

W. ARTHUR ERNST.
